UNITED STATES PATENT OFFICE.

NORMAN L. SNOW, OF HARTFORD, CONNECTICUT.

SOOT-BLOWER ELEMENT.

Application filed October 10, 1921. Serial No. 506,767.

This invention relates to the construction of blower elements of soot-blowers. These elements commonly consist of tubular headers or pipes provided with discharge nozzles along their length, and they are arranged across or adjacent to the tubes of steam boilers in such manner that they may be rotated to direct jets of steam admitted to the blower element onto the boiler tubes to remove soot, ash and kindred products of the fuel combustion therefrom. In the prior structures the header pipes are usually each provided with a single row of holes, and nipple-like nozzles are screwed, headed or welded therein to direct the steam jets. Although such holes and their individual nozzles occasionally occur at diametrically opposite points, they have no structural connection but are so located for particular cleaning purposes. Blower elements, being subject to high temperatures by the flames and gases of combustion from the furnace, are liable to warp, twist and deteriorate in such manner that they cannot be easily rotated, and so that the nozzles are loosened and drop out thereby greatly diminishing the force and effect of the steam jets issuing from the holes.

The object of the present invention is to provide a blower element of this nature but with combined struts and nozzles so constructed and secured that they will stiffen and strengthen the header pipe, and will not loosen or drop out under the influence of heat. This object is attained by forming diametrically opposite holes in the header pipe, preferably of equal size so as to equalize expansion strains, and in assembling therein struts which extend diametrically across the interior of the pipe, said struts having jet-nozzles formed in one or both ends thereof, thus strengthening the pipe against warpage and effectually preventing dislocation of the nozzles owing to their mechanical fastening on opposite sides of the pipe.

In the accompanying drawings, Fig. 1 shows a section of a boiler provided with a soot blower element that embodies the invention. Fig. 2 on a larger scale, shows a section of a blower pipe and a combined strut and nozzle constructed and secured as described. Fig. 3 is a similar section with a tubular strut-nozzle of modified form.

Fig. 4 shows another form of tubular strut-nozzle secured according to the present invention. Fig. 5 shows another modification.

For the purpose of illustrating the use of the improved blower element, it is shown in connection with a water tube boiler in which the blower element is arranged to extend across the water tubes 1 that are supported below the steam chambers 2 within the boiler setting 3 in the usual manner. The blower element consists of a header pipe 4 that is supported within the boiler setting in bearings mounted on some of the water tubes and that extends through one wall of the setting. On the outside the header is provided with means 5 through which steam may be admitted and with means 6 by which the element may be rotated. The blower pipe 4 has a series of diametrically opposite holes spaced at suitable intervals along its length. The struts 7 extend across the interior of the pipe through these holes and are enlarged at each end or otherwise secured to the pipe. A jet throwing nozzle may be formed at one end of the strut as shown in Figs. 3 and 5 or at both ends as shown in Figs. 2 and 4. Such nozzles may be straight as shown in Fig. 4 or they may be flared as shown in Figs. 2, 3 and 5 to form a diverging path of discharge.

Openings 8 are made through the struts near the middle of their length for the passage of steam from the header pipe into the nozzles, which openings may be of any desired size or shape as indicated in the several figures.

In all cases the struts pass across from one side of the blower pipe to the other and are headed over at their ends or otherwise positively fastened to the pipe in such manner as to prevent them from loosening. The symmetrical perforation of the blower pipe tends balance and neutralize the expansion or contraction strains of heating thereby tending to remove a common cause of warpage, and the location, construction and method of securing the struts stiffens the pipe and reduces its liability to sag, particularly should the struts be in a vertical position when the blower element is not in active use.

Warpage in soot blower elements is generally produced by inequalities in the temperature of the walls of the element. This dif-

ference may exist due to one side of the element being more highly heated than the other as it lies idle in the boiler. For example, the bottom of the element may be subjected to direct impingement of the flame, thus producing a higher temperature in the bottom wall of the pipe. When steam is admitted to the blower element in the normal operation of the same, condensate is frequently carried in with the steam and brought into contact with parts of the blower walls. The parts with which the water contacts are subjected to a greater chilling effect than those parts with which the steam alone contacts, thus causing an unequal cooling.

If one portion of a blower element is heated to a different temperature than the other portion, it is obvious that unequal expansion or contraction results, thus leading to warpage of the blower pipe. It is obvious that the use of the diametral struts as herein described resists this differential expansion or contraction and thus resists warpage of the element. If one side of the blower pipe tends to expand or contract ahead of the other, the action of the strut is such as to resist this tendency.

The invention claimed is:

1. In a boiler cleaner, a soot blower element adapted to be positioned within a boiler setting for discharging a jet of cleaning fluid adjacent parts of the boiler to be cleaned, said element comprising a pipe formed with an opening, means for conducting a cleaning fluid to said element, and a member engaged in said opening and having a portion thereof provided with a passage adapted to conduct the cleaning fluid from within the element for discharge laterally of the element through said opening, said member being also formed with a second portion engageable with said element, said portions of said member cooperating to resist distortion of the element under the influence of temperature differences, said second portion extending substantially in the opposite direction from said first portion, and also provided with a passage adapted to conduct cleaning fluid from within the element for discharge laterally thereof.

2. In a boiler cleaner, a soot blower element comprising a pipe adapted to be positioned within the boiler setting and provided with diametrically opposite openings at intervals along its length, diametral struts passing through the tube and secured in said holes for resisting distortion of said element under the influence of temperature differences, said struts having passages respectively for conducting cleaning fluid from within the element for discharge laterally thereof.

3. In a boiler cleaner, a soot blower element comprising a pipe adapted to be positioned within the boiler setting and provided

with diametrically opposite openings at intervals along its length, diametral struts passing through the tube and secured in said holes for resisting distortion of said element under the influence of temperature differences, said struts having passages respectively for conducting cleaning fluid from within the element for discharge laterally thereof, through said diametrical opposite openings.

4. In a boiler cleaner, a soot blower element comprising a pipe adapted to be positioned within the boiler setting, a strut for resisting distortion of said element under the influence of temperature differences, said strut also forming a nozzle for discharging cleaning fluid in diametrically opposite directions and having a passage for admission of a cleaning fluid thereto.

5. A soot blower element comprising a pipe with a plurality of pairs of oppositely disposed openings spaced along its length, and a plurality of nozzle forming members, each engaged in a pair of said openings, the opposite ends of said members being spread laterally into engagement with the outer surface of said element.

6. A soot blower element comprising a pipe provided with a pair of oppositely disposed openings, and a nozzle forming member having ends engaged in said openings respectively, said member being provided with means for conducting a cleaning fluid from within the element for discharge laterally thereof through said openings.

7. A soot blower element comprising a pipe having pairs of oppositely disposed holes at intervals along its length, nozzle forming members extending across the pipe through said holes and enlarged on the outer ends for securing engagement with the pipe about said holes.

8. A soot blower element comprising a pipe, said pipe being provided with a pair of oppositely disposed holes, and a nozzle forming member extending across the pipe and terminating in enlarged heads fixed in the said oppositely disposed holes.

9. A soot blower element comprising a pipe, said pipe being provided with a pair of oppositely disposed holes, and a nozzle forming member extending across the pipe and terminating in enlarged heads fixed in the said oppositely disposed holes on the outside thereof.

10. A soot blower element comprising a pipe and nozzle forming members with openings through their walls communicating with the channel in said pipe, said members extending across the pipe and through the opposite walls thereof and each having provision for discharging cleaning fluid jets in substantially opposite directions.

11. The combination with a soot blower element, of a plurality of spaced nozzles

mounted in said element and each having an inlet within said element and flaring from said inlet to its outlet and each of said nozzles also having portions engageable with the opposite walls of the element for resisting distortion of the element.

5 12. A nozzle forming member having portions engageable with opposite walls of

a soot blower element, and having a cleaning fluid inlet intermediate said portions, and means for conducting a cleaning fluid from said inlet laterally of the element in opposite directions for discharge through said first named portions of the nozzle member.
